RECEPTACLE FOR STORING TOBACCO
PRODUCTS

Henry Handschur, Winfield, N. Y.

Refiled for (abandoned) application Serial No. 578,814, December 3, 1931, which in turn is a division of Serial No. 487,843, October 10, 1930. This application November 27, 1935, Serial No. 51,974.

1 Claim. (Cl. 217—3)

This invention relates to receptacles, and more particularly it pertains to receptacles which are employed for the purpose of storing of cigars or other tobacco products to maintain them at all times in proper condition, and this application is a substitute, in whole, of my abandoned application Serial No. 578,814 filed December 3, 1931, as a division of my application, filed October 10, 1930, Serial Number 487,843.

It is one of the objects of the invention to provide a receptacle in which, when its cover is closed, an air-tight closure joint is formed between the cover and the body proper of the receptacle.

It is a further object of the invention to so construct a receptacle of the aforementioned character in which the cover, although of the hinged type, engages with the body of the receptacle throughout the entire defining edge of its open side, thus insuring a tight joint at all times when the cover is in its closed position.

Other objects of the invention relate to certain novel and improved constructions, arrangements and combinations of parts hereinafter described and particularly pointed out in the claim, the advantages of which will be readily understood and appreciated by those skilled in the art.

The invention will be clearly understood from the accompanying drawings illustrating the invention in its preferred form, and the following detailed description of the constructions herein shown.

In the drawings:

Figure 1 is a perspective view of a receptacle constructed in accordance with the present invention, the receptacle being shown in its open position.

Figure 2 is a detail sectional view taken through the cover on the line 2—2 of Figure 1.

Figure 3 is a detail perspective view illustrating a portion of the cover.

Figure 4 is an inverted fragmentary view of a portion of the cover.

Figure 5 is a transverse sectional view of the receptacle on an enlarged scale showing the cover in its closed position, and

Figure 6 is an enlarged fragmentary sectional view showing the cover in its partially open position.

Referring specifically to the drawings, 10 indicates the body of the receptacle, 11 the cover thereof, and 12 indicates the hinges by which the cover is hingedly connected to the receptacle body.

By reference to Figure 5 it will be noted that the body of the receptacle 10 is provided with a relatively thin metallic lining 13, and within said

lining 13, there is provided an insulating material 14 of which "Celotex" is a good example of the material used. Within the insulating wall 14, the receptacle is lined with wood or the like 15, and these several walls which make up the lining, are held in position by turning the lining 13 over the upper edge of the insulating lining and the lining 15 as indicated at 16 in Figure 5, and extending the folded in edge downwardly within the receptacle as indicated.

Thus it will be seen that by the construction herein set forth, the metal lining 13 and the lining walls 14 and 15 are securely held in position within the receptacle without resorting to separate fastening means of any kind since the folded over portion 16 of the lining 13 serves to secure all parts within the receptacle.

The cover 11 is preferably formed from wood, and has a metallic lining 17. Projecting from the inner base of the cover 11, and depending therefrom when the cover is in its closed position, there is a metallic extension 18 which is hollow as shown, and is provided with an outwardly flaring flange 19 defining its free edge.

Surrounding this hollow extension 18, there is a follower or the like which as illustrated in Figures 2 and 3, comprises a rectangular frame 20, which is provided on its exposed edge, with a groove 21 which extends entirely around said frame. Upon that face of the frame opposite to the groove 21, said frame is provided with a plurality of spaced recesses 22, for the reception of coil springs 23, which exert their tension in such a manner as to force the rectangular frame 20 outwardly of the cover.

Means is provided to prevent the rectangular frame 20 being forced entirely from the cover, and this means consists of a flange or the like 24 which defines the open edge of the cover, and is mounted therein, and this flange 24 together with the flange 19 heretofore mentioned as projecting from the open edge of the member 18, forms a stop to prevent the rectangular frame member 20 being forced from the cover as more clearly illustrated in Figure 6.

Bridging the groove or channel 21 in the frame like member 20, there is a closure forming member 30. This closure forming member 30 preferably comprises a piece of flexible material such as chamois or similar material, and it is held in position at one end between the shoulder forming member 24 and the inside face of the side walls of the cover 11, and at its other edge, it is secured to the inner face of the frame like member 20 as indicated at 32 in the drawings. The

closure member 30 will contact with the up-standing flange or shoulder 16 throughout the entire length thereof, and will provide an air tight joint therewith. This result is obtained by reason of the fact that the frame like follower 20 is resiliently mounted by means of the spring 23, and that as the cover is moved to closed position, the several springs 23 are placed under compression, and the frame like follower 20 is free to assume any irregular position which may be necessary for the sealing strip or member 30 to engage with the defining shoulder of the receptacle throughout its entire length as best illustrated in Figure 5.

15 By reason of the manner in which the sealing strip 30 is secured in position, an air tight joint between the cover and the body of the receptacle is formed for the reason that air entering the joint between the cover and the receptacle is admitted to the interior of the receptacle exteriorly of the flange or shoulder 16 and inasmuch as the sealing strip contacts with the upper edge of this flange or shoulder 16 air entering at this point is excluded from the interior of the receptacle.

20 From the foregoing, it will be apparent that the present invention provides a receptacle for cigars, cigarettes and other articles in which the air is positively excluded from the interior of the receptacle when the cover is in its closed position, thus providing a highly efficient receptacle for any article which it is desirable to store under such conditions.

From the above it will also be appreciated that due to the air tight joint between the cover and the body of the receptacle and the provision of the insulating wall 14 impairment of the flavor of the tobacco, either by loss or by accretion is effectively prevented.

10 While the invention has been herein disclosed in a preferred form, it is to be understood that the invention is not to be limited to the specific constructions herein illustrated, and that it is capable of various other adaptations without departing from the spirit thereof.

Having thus described the invention, what is claimed as new and what it is desired to secure by Letters Patent of the United States, is:

15 In a receptacle of the character described, a receptacle body, a lining therefor, said lining being formed of relatively thin metal, an insulating wall, the upper edge of which projects above the open side of the receptacle body, a lining wall 20 the upper edge of which projects beyond the upper edge of the insulating wall to provide a shoulder defining the open edge of the receptacle body, and means for securing said insulating wall and said lining walls in position, said means comprising a portion of the metallic lining bent across the upper edges of the insulating wall and lining wall and over the shoulder formed by the lining wall, and then downward flatly into contact with the inner surface of said lining wall.

30 HENRY HANDSCHUR.
